UNITED STATES PATENT OFFICE.

EDWIN T. GREENFIELD, OF NEW YORK, N. Y.

MECHANISM FOR LINING METAL TUBES WITH PLIABLE MATERIAL.

SPECIFICATION forming part of Letters Patent No. 595,472, dated December 14, 1897.

Application filed April 29, 1897. Serial No. 634,362. (No model.)

To all whom it may concern:

Be it known that I, EDWIN T. GREENFIELD, a citizen of the United States, residing at New York, in the county of New York and State of New York, have made a new and useful Invention in Mechanism for Lining Metal Tubes with Pliable or Fibrous Material, of which the following is a specification.

My invention is directed to improvements upon an invention disclosed in a prior patent granted to me by the United States Patent Office on the 27th day of October, 1896, and numbered 570,165, and will be fully understood by referring to the following specification and accompanying drawings, in which—

Figures 1 to 5, inclusive, illustrate in side elevational view, and Figs. 1^a to 5^a, inclusive, in plan view, the entire apparatus, consisting of two complete machines arranged side by side and upon a single set of standards or supports. Fig. 6 is an end elevational view as seen looking at Figs. 5 and 5^a from right to left, and Fig. 7 is an enlarged sectional view of the clutch-controlling apparatus which regulates the governing mechanism for governing the speed at which a tube shall be lined. Fig. 8, Sheet 1, is a detail sectional view of one end of the pneumatic-pressure tube and a spring-pressed piston connected thereto. Fig. 9 is a longitudinal sectional view of the inflating-mandrel and means for protecting the same as it is moved backward and forward through the tube to be lined. Fig. 9^a is a transverse sectional view of Fig. 9, taken on the line x x, and as seen looking from left to right in the direction of the arrows. Fig. 10 is an enlarged side elevational view of the controlling-valve, showing also the connections to the air-supply and air-pressure pipes. Fig. 11 is a sectional and perspective view of the interior rotary portion of said valve, the section being taken on the line x² x², Fig. 12. Fig. 12 is a longitudinal sectional view of the valve, taken on the line x' x', Fig. 10, and as seen looking at that figure from left to right in the direction of the arrows. Fig. 13 is a sectional view taken on the line x³ x³, Fig. 12; and Fig. 14 is a similar sectional view taken on the line x⁴ x⁴, Fig. 12.

My invention has for its objects, first, the centralization of the air-controlling valves

of the apparatus at a given point where they are all automatically operated by the movement of a tube-carrying carriage; second, the application of a governing mechanism in connection with the pneumatically-actuated mandrel, which shall govern the speed at which a tube shall be lined; third, to provide means for holding the tubular lining in its tubular state and with reasonable rigidity after it is drawn, so that when it is forced into the tube to be lined there will be no danger of buckling or the presentation of irregular lines or creases to the interior wall of said tube; fourth, to provide means for cooling the paper or fibrous tubing after it has been subjected to the ironing process, so that it will not cause the paste to dry before it enters the tube to be lined; fifth, to provide means for causing the mandrel to be moved forward a short distance after a tube has been lined and severed, so as to insure no waste of material and supply a full or complete lining for each successive tube to be lined; sixth, to provide means for protecting the expandible mandrel from abrasure or injury.

Referring now to the drawings in detail and first to Figs. 1 to 6, inclusive, S S S represent four triangular-shaped legs or standards secured to the floor and supporting on their upper ends a T-shaped metallic frame A, which acts as a base for the entire apparatus. The mechanism, it will be noticed, is illustrated in duplicate and is controlled in its operations from a single source of air-supply, (not shown,) but connected by an air-pipe T, Fig. 4, and cock v' with two controlling-pipes p p, having cocks v² v², each of said pipes being connected to an independent main controlling-valve V, so that in describing the apparatus it will be understood that all duplicate letters or figures of reference refer to duplicate parts of the two independent sets of apparatus, which are thus arranged in practice for convenient manipulation from a single source of air-supply.

P² is a metallic tube, about eleven feet in length, secured by standards S' S' to the base A and provided with a hollow piston-rod P³, piston-head H', (see Fig. 8,) and stuffing-boxes S B and S' B' at its opposite ends, said piston-rod being substantially like that disclosed in my prior patent and having its outer

or exposed portion beyond the stuffing-box S B provided with perforations $k k$ and surrounded with a close-fitting sleeve R', of soft rubber, secured at its opposite ends to the 5 perforated mandrel by nuts N N, so arranged that the junctions between the ends of the sleeve R' and the hollow mandrel are airtight.

t t t is a series of thin steel strips surrounding the sleeve R' and attached at their opposite ends to collars N' N', there being sufficient play between the ends of these collars and the nuts N N to allow for the expansion of the sleeve R' when subjected to pressure,

15 the function of these metallic strips being to protect the rubber sleeve against abrasure or to prevent any injury thereto while it is being inserted into or withdrawn from the tube to be lined.

20 P R (see Fig. 8) is a rod provided with a perforated buffer-head B H and a spiral spring Sp, located in one end of the tube P², the function of these parts being to advance the piston-rod P³ a definite distance after the air-pressure has been removed from behind the 25 piston-head H', so as to cause the inflating-mandrel to advance slightly, as will be more particularly described in connection with the description of the mode of operation.

30 R³, R⁴, and R⁵ are reels journaled beneath the base A, the reels R³ and R⁴ being adapted to hold strips of paper D' D' and the reel R⁵ a strip of oil-cloth D², r² r², r³ r³, and r⁴ r⁴, Fig. 2, being guide-rolls for the two latter 35 strips, and P' a paste-box adapted to cover both sides of the paper strip D' with paste, the upper surface only of the strip D² being coated with paste as it passes beneath a supplementary box Z.

40 K K' are suitable tube-forming dies, in this instance not substantially different from the like parts disclosed in my prior patent and designed to give to the two strips of paper and strip of oil-cloth the necessary conformation as they are advanced in the course of 45 operation.

M' is a heating-die, and p⁴ a gas-pipe connected with a supply of gas, v² being a cock adapted to admit the necessary gas to burners 50 b b' beneath the heating-die M', said parts acting substantially as in the manner disclosed in my prior patent above referred to.

M² is a cooling-die consisting of a water-jacket operatively connected with a pipe p⁵, 55 the arrangement being such as to convey a supply of cold water around a close-fitting sleeve which surrounds the completed drawn tube, so as to cool it as quickly as possible, and p⁶ is a junction-pipe joining one of the 60 cooling-dies M² with the other, the outlet being a waste-pipe. (Not shown.) These several parts K, K', M', and M² are supported upon a supplemental base T', which in turn is sustained upon the main base A by standards 65 S² S² S², as clearly shown.

p' is an air-supply pipe running from the valve V, Fig. 4, to the extreme end of the

tube P² and entering it at the point q (see Fig. 8) behind the piston-head H. p² is a similar air-supply pipe running from the 70 same valve V to the other end of the tube P² and adapted to enter said tube against the reverse side of the piston-head H'. (See Fig. 2.)

G³ is a guideway secured upon the standards S, (see Figs. 3 and 3^a.) and adapted to sustain a number of sliding eyes or rings e e, said eyes or rings being of substantially the same interior diameter as the composite tube, which is formed from the strips D D' D² as they 80 emerge from the die K'. These eyes are connected together by a chain c and adapted to assume various positions upon the completed tube as it is drawn forward, they all being grouped together at the extreme left before 85 said tube is thus drawn.

Referring now to Figs. 4, 4^a, 5, 5^a, and 6, K² represents a carriage sustained by rolls R R R and guiding-eyes e' e' e' upon a runway A³ and the guideway G³, (see Fig. 7,) said parts in turn being supported by lateral arms A' A' and n n above the frame A. (See Fig. 6.) To the upper side of this carriage is secured supporting or carrying brackets m m and a back-stop O, with a front ledge or support O' 95 for sustaining the tube B to be lined, said tube being shown in dotted lines. H² H² H² are handles attached to the carriage K² for moving it forward to its starting position. G⁴ G⁵ are sprocket-wheels journaled in arms 100 or supports carried by the base A beneath the carriage K² and supporting a sprocket-chain s', attached at any convenient point to some part of said carriage, the function of which is to act as a governor for a definite 105 portion of the movement of the carriage under the pressure of the pneumatic part of the apparatus and positively for another definite portion of said movement after the pneumatic pressure is removed, its positive action being 110 to draw the tube forward. G⁶ is a second sprocket-wheel running loosely upon a shaft s⁵ and adapted to bear frictionally against the sprocket-wheel G⁵, (see Fig. 7,) V² being a pneumatic valve provided with a piston-head P², adapted to bring the sprocket-wheel 115 G⁶ into frictional relation with G⁵ at the proper time, n' n' being ball-bearings and o oil-holes for properly oiling the parts, the valve V² being connected by a pipe p³ with 120 the controlling-valve V. g, g', g², and g³ are stops adjustably supported in slots in depending arms carried by the carriage K², the function of said stops being to operate the valve V through the agency of operating-arms 125 I I'. (See Fig. 4.)

Referring now to Figs. 10 to 14, inclusive, for a detailed description of the main controlling-valve, it will be seen that this valve is of a double cylindrical form, the outer portion 130 being provided with three outlets designed for exhausting the air at the desired time, while the inner portion V' is provided with an inlet-port I V and three inlet or supply

ports S' V' , S^2 V^2 , and S^3 V^3 , E' V' , E^2 V^2 , E^3 V^3 being oblong exhaust-ports adapted to connect the pipes p' , p^2 , and p^3 with the exterior air at the proper time, so as to exhaust.

5 U is a check-rod provided with a spring S⁴ and a roller J, adapted to fall into the successive notches n³ as the valve is moved into its successive positions.

In the apparatus illustrated in the drawings 10 the piston-head H' is shown as being near the extreme left-hand end of its surrounding pneumatic tube or cylinder P², so that the free end of the piston which carries the expansible sleeve R' is located slightly to the 15 right of the last forming-die K' (see Figs. 8, 2, and 2^a), and the strip of pliable or fibrous material D is shown as just entering the forming-die K, while the additional strips of fibrous or pliable material D' and oil-cloth D² are 20 shown as entering the second forming-die K'.

In describing the mode of operation, therefore, it will be understood that it is necessary, first, to pass the strip of fibrous or pliable material D by hand through the die K, the heating-die M', cooling-die M², and final forming-die K' and the additional strips through said forming-die, and, finally, to draw all of said strips forward in their completed tubular form and pass them through the eyes or rings e e 30 until one length of completed composite tubular lining is formed, with its free end resting at a point slightly in front of the carriage K², Fig. 4. The fibrous or pliable strip D' is covered on both sides with a coating of paste 35 as it passes through the paste-pot P', and the oil-cloth strip D² is pasted upon the upper side only, the painted or coated portion of said oil-cloth being upon the lower side, so that it (the painted portion) is caused to adhere to the 40 inner wall of the tube when lined therewith, and the three strips are firmly cemented or pasted together. The tube B to be lined is laid upon the carriage K² so that its rear end rests in the socket O and its front end upon 45 the ledge O', its intermediate portions resting upon supports m m. The attendant now takes hold of one of the handles H² and moves the carriage to its extreme left limit, thereby causing the already-formed section of tubular lining 50 to enter said tube and force the eyes or rings e e to the left about said formed section of tube until they are grouped together at a point over the supporting-standard S, Fig. 3. The cocks v' v² having been previously turned 55 to such positions as to admit air from the source of air-supply through the pipes T and p to the valve V, there results, as the carriage passes, the following action upon the rotatable part V' of the valve V: First, the stop g' on 60 striking the arm I gives to the rotary part V' of the valve V a partial revolution, causing it to turn into such position that the exhaust-port E² V² on the rotary part V' of the valve V is brought beneath the inlet of the pipe p², leaving this pipe open to the free air, no result 65 following this action in the first operation, but an important result following it during

the operation of the machine, as will be described later on. When the carriage reaches its extreme left-hand position, the stop g' at 70 the right-hand end thereof comes into contact with the second controlling-arm I' of the rotary part of the valve V and rotates it an additional step, thereby bringing the supply-port S' V' into alignment with the opening to 75 the pipe p'. Consequently compressed air enters said pipe and passes into the pneumatic-pressure cylinder of tube P² at the point q, passing thence through the hollow piston P³, in the same manner as described in 80 my prior patent, to the hollow expansible mandrel now located inside of the composite tubular lining and tube to be lined. This pressure, as described in said patent, causes the lining first to adhere to the inner wall of 85 the tube and then to carry the tube and its supporting-carriage in a reverse direction. At the same time that air entered the pipe p' through the rotary part V' of the valve V a second inlet-port S³ V³ was brought into alignment with the third pipe p³, (see Figs. 4 and 25 14,) thereby admitting air through said pipe to the interior of the clutch-controlling valve V², Fig. 7, and causing the movable part P² thereof to force the shaft s⁵ and its supported 90 continuously-driven sprocket-wheel G⁶ firmly against the sprocket-wheel G⁵, so that the movement of the constantly-driven sprocket-wheel G⁶ is now imparted to the temporarily 95 stationary sprocket-wheel G⁵ and in a direction such that the lower half of the sprocket-chain s', which is secured to the carriage, is now moving under the action of the pneumatic pressure, but at a stated speed, so that 100 any tendency on the part of the pneumatic pressure to suddenly force the lined tube and its supporting-carriage to its extreme right-hand position will be regulated or governed by this constantly-driven sprocket apparatus, which travels at a regular speed. As the carriage 105 returns under this action to its normal position the strips of paper D D' and oil-cloth D² are drawn forward from their reels R³, R⁴, and R⁵ and through the dies K, M', M², and K', and the next section of lining-tubing is 110 formed, the heating-die performing the same function as the like part performed in my prior patent and the cooling-die eliminating the heat, so as to prevent the drying of the paste, and as the completed composite tube 115 is thus drawn forward the guiding or sustaining eyes or rings e e e are caused to maintain said tube in a perfect tubular form as they are separated the one from the other and properly spaced by the chain c, which 120 joins them. As the carriage returns in the manner already indicated the stop g' comes first into contact with the arm I', reversing the rotary movement of the part V' in such manner as to place the exhaust-valve 125 E' V' in the position shown in Fig. 13, thereby exhausting the air from the pneumatic-pressure tube p' and the expansible mandrel R'. The carriage and its supported tube are 130

now moved under the positive action of the sprocket-chain s' and the positively-propelled sprocket-wheel G^6 , which in turn is actuated by a constantly-driven source of power at any desired speed through a sprocket-chain S^3 . This positive movement is continued for a brief distance until the stop g comes into contact with the arm I , thereby rotating the rotatable part V' of the valve V an additional step to the right until the exhaust-port $E^3 V^3$ of the rotary part V' of the valve V is brought into position to exhaust the air behind the movable part of the clutch-valve V^2 , Figs. 7 and 14. When this occurs, the carriage stops and the apparatus is again ready to be advanced for the lining of another tube. It will be noticed that when the rotary part V' of the valve V assumes the position shown in Fig. 4, owing to the action of the stop g , the supply-port $S^2 V^2$ was placed in such position as to admit air to the pipe p^2 . (See Fig. 10.) Consequently this inflow of compressed air behind the piston-head H' caused the piston P^3 to return to its extreme limit, (shown in dotted lines in Fig. 8,) and the machine stands in this position, with the piston-head held firmly against the pressure-rod $P R$, acting thus against the continued strain of the spiral spring Sp . Consequently the free end of the expandible mandrel R' is now at a point slightly to the left of the support O' and thus remains until the tubular lining is severed, after which an additional pipe to be lined is laid in place and the attendant now taking hold of the handle H^2 moves the carriage to the left, as before, whence the stop g' , striking the arm I , rotates the rotary part V' of the valve V , in the same manner as before described, until the exhaust-port $E^2 V^2$ is opposite the inlet of the pipe p^2 , (see Fig. 10,) thereby exhausting the air in the pipe p^2 and the pneumatic-pressure tube P^2 behind the piston-head H' and allowing the spring-pressed rod $P R$, under the action of the spring Sp , to force said piston-rod P^3 , and hence the mandrel R' , a few inches to the right, thus carrying it to the extreme end of the exposed portion of the lining and enabling the attendant to utilize all of the lining without waste. The carriage is now moved to the left, as before, by hand, and the operation continued indefinitely.

Although I have hereinbefore described my improved apparatus as applicable to the lining of tubes with paper, oil-cloth, or other fibrous or pliable material, I do not limit it to such uses, as it is obvious that it may be utilized in the lining of tubes with strips of rubber, or, in fact, any material which is sufficiently pliable to admit of use in the manner described.

It is also obvious that the apparatus may be used for the purpose of drawing tubes from thin sheets of paper, or, in fact, any material which may be used for the forming of tubes by drawing processes, and my claims herein-

after made are to be construed as of such scope as to cover, generically, all such uses.

Having thus described my invention, what I claim, and desire to secure by Letters Patent of the United States, is—

1. Mechanism for lining tubes with pliable or fibrous material consisting of means for forming a tube from strips thereof, means for inserting said tube within the tube to be lined and then inflating it, a carriage for carrying said tube and a controlling-valve for regulating the operation of said parts, in combination with valve-controlling means carried by the carriage, substantially as described. 80

2. Mechanism for lining tubes with pliable or fibrous material such as paper, consisting of means for forming the tube-lining of the pliable material, and additional means consisting of an expandible mandrel or tube for causing the previously-formed tube to adhere to the inner wall of the tube to be lined, in combination with regulating or governing mechanism for regulating the speed at which the mechanism shall operate, substantially as 90 described.

3. Tube-lining mechanism consisting of means for inserting a previously-formed tube of pliable or fibrous material such as paper within a tube to be lined, in combination with 95 additional means for holding or maintaining the lining in its tubular form while it is being formed and inserted into the tube to be lined, substantially as described.

4. In a tube-lining machine a series of eyes 100 or rings adapted to surround the lining as it is being drawn, said rings being joined together but having independent movement, substantially as described.

5. Mechanism for forming a tube of pliable 105 or fibrous material, such as paper, consisting of a die adapted to give to said material a tubular shape or conformation as it is drawn forward, means for heating this completed tube so as to iron it into shape, means for 110 coating additional strips of fibrous material with paste and additional means for giving to the additional strips a tubular form, in combination with means for cooling the first-named tube so as to delay the action of the 115 adhesive agent, substantially as described.

6. In a tube-lining machine means for constructing the lining from pliable or fibrous material and inserting it into a tube to be lined, in combination with means for causing 120 the inserting mechanism to partially advance the lining within the tube before the latter is forced forward to its extreme limit around the lining whereby a waste of lining material is avoided and each tube supplied with the 125 required length thereof, substantially as described.

7. In a tube-lining machine an expandible sleeve provided with means for preventing injury thereto, substantially as described. 130

8. In a tube-lining machine an expandible sleeve secured at its opposite ends to a hol-

low perforated piston, in combination with protecting means surrounding said sleeve and expansible therewith and adapted to protect the same from injury, substantially as described.

5 9. A tube-lining machine consisting of pneumatically-controlled mechanism adapted to form and expand a lining of pliable or fibrous material within a tube to be lined, in combination with a carriage adapted to carry said tube over the lining and means operatively connected with the carriage adapted to govern the speed at which the lining-tube shall be drawn, substantially as described.

10 10. A tube-lining machine consisting of pneumatically-controlled mechanism for forming and lining a tube with pliable or fibrous material, in combination with pneu-

matically-controlled governing mechanism adapted to control the speed at which the tubular lining shall be drawn, substantially as described.

11. A tube-lining machine consisting of pneumatically-controlled mechanism adapted to form a tubular lining and expand the same within a tube to be lined, in combination with a single controlling-valve and a pneumatically-controlled speed-governor, all of said parts being controlled in their movement by said valve, substantially as described.

In testimony whereof I have hereunto subscribed my name this 21st day of April, 1897.

EDWIN T. GREENFIELD.
